UNITED STATES PATENT OFFICE.

GEORG C. SCHÜLE, OF HERISAU, SWITZERLAND, ASSIGNOR TO OTTO SCHÜLE, OF NEU ST. JOHANN, SWITZERLAND.

FLYING-MACHINE.

1,247,727.

Specification of Letters Patent. Patented Nov. 27, 1917.

Application filed December 16, 1915. Serial No. 67,185.

To all whom it may concern:

Be it known that I, GEORG C. SCHÜLE, a citizen of the Republic of Switzerland, residing at Herisau, Switzerland, have invented certain new and useful Improvements in Flying-Machines; and I do hereby declare the following to be a full, clear, and exact description of the invention, such as will enable others skilled in the art to which it applies to make and use the same, reference being had to the accompanying drawings, and to letters or figures of reference marked thereon, which form a part of this specification.

The present invention relates to an improved mechanism for cross-stabilizing or balancing flying machines, which may be operated automatically or by hand, and which makes use of the atmospheric influences, which are apt to injuriously affect the vertical position of the machine, in setting up counter-moments, allowing at the same time the operator then wilfully to retain the position into which such lateral influences have tilted the machine. This is obtained by providing an upper and a lower stabilizer, to be called into service independently of one another, but preferably combined, when both stabilizers may be operated in conjunction or separately. In the lower balancing device either end of a cable is resiliently attached to opposite sides of the car, which latter is suspended from the frame work with capability of oscillating in lateral direction only, the cable being guided over fixed points disposed laterally outside of the axis of oscillation. The upper balancing device comprises a pendulous lever, to the lower end of which are resiliently secured the ends of a cable which is guided over fixed points disposed laterally without the axis of oscillation of said lever and coöperates with a drum, located in the oscillation axis of the lever and serving for operating special steadyng surfaces secured to the lateral wings. In case both of these stabilizers are provided on the same machine, provision may be made whereby the driver can operate both mechanisms at will, and the pendulous lever and swinging car may be temporarily rigidly connected.

In order to make my invention more read-

ily understood, I will now describe it in detail with reference to the accompanying drawings, in which:

55

Figure 1 represents a side elevation,

Fig. 2 a front view,

Fig. 3 a fragmentary plan,

Fig. 4 part of Fig. 1, on an enlarged scale and partly in section,

60

Fig. 5 a detail in plan,

Fig. 6 a section on line A—B of Fig. 5,

Fig. 7 a section on line C—D of Fig. 5,

Figs. 8 and 9 respectively show diagrammatically and perspectively the cable layout.

65

The car 1 is suspended from the machine frame by the hangers 2, suitably secured in pairs to the car sides and forming ball bearings 3 at the upper converging ends. The inner bushes of these ball bearings are fixed on the shafts 4, which latter are journaled with no axial play in bearing brackets 5 forming part of the body or frame 6. This arrangement allows of the car swaying to and fro in a cross-wise direction. To take up the axial end-thrust there are provided converging braces 7, respectively secured to the rearmost hanger pair and forming at the top the bearing 8, which together with the thrust bearings 9 is supported on the shaft 10, which latter in turn is journaled with no relative axial displacement in the brackets 11 rigidly secured to the machine frame 6.

70

In a bearing standard 12 in the car 1 is journaled a shaft 13 to which are fixed the cable drum 14 of a cable 15 and a sprocket 15^a. Several turns of the cable 15 are laid around this drum, and the two cable-ends are guided over pulleys 16, which are hung up on the machine body laterally of the axis of oscillation of the car and somewhat above it, as shown in Fig. 2. The cable-ends then return to the car and are resiliently secured thereon, for instance by means of spring-barrels 17 of well known type. If at one point of the cable a pull is exerted, the spring will be put under tension and part of the cable rolled up in the respective barrel will unwind. If, on the other hand, the normal pull on one end of the cable is eased, then the spring will again draw-in part of the previously withdrawn cable.

75

Within easy reach of the driver are pro-

90

95

100

vided bearing blocks 18 one of which journals the shaft 19 direct, while the other rotatably houses the sleeve 20, which in turn journals the shaft 19 (Fig. 6). To the sleeve 20, which, as it were, constitutes a shaft by itself, is rigidly secured a hand-wheel 21 and a chain-wheel 22, which latter is operatively connected with the sprocket 15^a by the chain 23. The hub of the handwheel 21 10 constitutes a toothed wheel 24. The bearing 18 next to the toothed wheel 24 has a disk-shaped enlargement 25, provided with a solitary notch equal in dimensions to the gap between each two teeth of the wheel 24. 15 Into this notch and any tooth gap can engage simultaneously the wide blade 27 of a double-armed lever 29, which is rotatable about the pin 28 supported by the bearing 18, and to the other end of which is linked one end 20 of a draw rod 30, whose other end is pivotally secured to the hand lever 31, which in turn is rotatably secured with its lower end to a stud 32 extending from the car 1, as clearly shown in Fig. 7. A leaf spring 33 25 is secured to the car and snaps with a pin 34 behind the lever 31 when the latter assumes its outermost position when laid over in the direction of the arrow.

If the handwheel 21 is for instance 30 rotated toward the right, which obviously can only be done if the blade 27 is not in the notch 26, the right-hand part of the cable 15 will be wound on drum 14 from out of the respective spring barrel 17, since 35 the cable drum 14 is forced by reason of the chain drive 22, 23, 15^a to follow the movement of the handwheel 21.

The left-hand part of the cable correspondingly slackens and the slack is drawn 40 into the respective spring barrel 17. If now the lever 31 is laid over as indicated by the arrow in Fig. 7, the blade 27 will take into the notch 26 of bearing 18 and also in between two teeth in the wheel 24. 45 This interconnects the car with the machine frame, since now the cable drum 14 can no longer be rotated and the cable mechanism cannot be operated one way or the other. This coupling between car and machine 50 body or frame can obviously be effected at any desired relative angle. The pin 34 of the leaf spring 33 locks the lever 31 and prevents its return, with the result that the blade 27 is securely retained in its locking 55 position until the driver pulls back the spring 33, which frees the lever 31 and allows it to swing back into the inoperative position.

On the shaft 19 (Figs. 5 and 6) is fixed 60 a handwheel 35 and a cable drum 36, around which latter several turns of a cable 38 are passed. Coming up from below one portion 38^a of this cable passes over a pulley 39 whose axis coincides with the axis of oscillation of the car in the constructional exam-

ple shown. It would suffice if this pulley 39, as well as an adjacent pulley 40, were located near the oscillation axis, and, again these two pulleys could also be rotatably secured to the underside of the one frame arm or 70 strut 5. The portion 38^b of the cable passes from pulley 39 (Figs. 2, 4 and 8) over a pulley 43 which is rotatably journaled on one end of a double-armed bracket 41 fast on the body 6. The succeeding portion 38^c 75 of the cable then extends toward a spring barrel 42, where the cable end is elastically secured to the housed spring. The other cable portion 38^d ascending from the drum 36 passes over the said pulley 40, then as 80 portion 38^e (Fig. 8) over a pulley 44, which is supported on the other end of the bracket arm 41, and finally as portion 38^f into the spring barrel 45. These two spring barrels are secured to the rear of a pendulous lever 85 46, whose axis of oscillation coincides with that of the car. For this purpose there is provided a smaller shaft 47, freely rotatable with one end in the short rigid shaft 4 (Fig. 4) and in the respective bearing 90 bracket 5. To this shaft 47 is rigidly secured the lever 46 as at 48, and the one end of this shaft extends freely into the cable drum 49, into whose other end, in turn loosely extends a pintle or gudgeon rigidly 95 held in a bracket bearing 51.

To the front face of the lever 46 are secured the two spring barrels 52 and 53 and a cable 54 is passed in several turns about the already referred to drum 49. The portion 54^a (Fig. 8) of the cable passes over a pulley 55 journaled coaxially of the pulley 48, and then as portion 54^b to the spring drum 52. The other cable portion 54^c passes over the pulley 56, which is journaled coaxially of the pulley 44, and the portion 54^d finally extends to the spring barrel 53. 100

Two more cables 57 and 58 (Fig. 9) are passed in several turns around the drum 49, their ends respectively extending to the 110 right and left and their lay-out being substantially identical. The portions 57^a and 57^b of the cable 57 pass over a guide pulley 59 to the cable pulley 60, which later is rotatably journaled in the hinge axis 61 of the 115 stabilizing planes 62 of the wing 63 and connected thereto by cables 64. The end of the section 57^b is carried around the pulley 60 a certain distance and then secured thereon. The cable section 57^c passes in turn 120 over the guide pulley 65, through the wing 63, over the guide pulley 66 located above the wing (Fig. 3) and finally, as section 57^d, to the cable pulley 60, where its end is secured in the manner of the other cable end, 125 as described above. The arrangement of the other cable 58 is identical to the one just described with reference to cable 57, the cable being guided over guide pulleys 67, 68, 69 to the cable pulley 60^a, situated in the 130

hinge axis 61^a of the stabilizing plane 62^a and connected thereto by means of the cables 64^a.

From the above it is clear that by the 5 oscillation of the lever 46, which serves as a pendulum, the stabilizing planes 62 and 62^a are automatically controlled, but can also be actuated at the will of the driver by manipulation of the handwheel 35.

10 For the purposes of combining the cross-stabilization by reason of the lateral oscillations of the car with the actuation of the stabilizing planes by the oscillations of the lever 46, the following arrangement has 15 been provided. To the front hangers 2 of the car is rigidly secured a bearing 70 (Fig. 4) provided with two cheeks 72 and 73, which are hinged together as at 71, forming a clamp. To the cheek 72 is secured a spindle 20 74, which is threaded at the farther end and carries a correspondingly threaded handwheel 75. Between this handwheel and the clamp cheek 73 is interposed a sleeve, loosely surrounding the spindle 74 and intended to 25 transmit the thrust of the handwheel, on the latter being rotated toward the right, to the cheek 73, which then causes the two cheeks to exert a clamping action. Turning back the handwheel, obviously, will release 30 the clamp again. In between these two clamp cheeks extends the lower portion of a disk 76 the upper part of which is rigidly secured to the short shaft 47 and thus partakes of the movements of the lever 46. If 35 the clamp 72, 73 is locked on the disk 76, it will be seen that the upper and the lower stabilizing devices must operate in unison.

By means of the handwheels 21, 35, 75 and the hand-lever 31 quite a variation of 40 cross-stabilizing maneuvers may be executed either manually or automatically. If, for instance, the handwheel 35 is turned toward the right, the rope section 38^a will be wound up onto the drum 36 and the section 38^a 45 will be correspondingly unwound therefrom, with the result, that the lever 46 will be tilted toward the right. If, however, the disk 76 is clamped in the clamp 72 by the operations of the wheel 75, which is possible 50 no matter what the relative angular position between lever and car, then the lever 46, now rigidly secured to the car, must partake of the latter's oscillations. The handwheel 35 and the drum 36 do not 55 rotate, since the pulleys 39 and 40 are situated in or near the axis of oscillation of the car.

In order to impart a high degree of rigidity to the entire machine, despite the pendulous suspension of the car, there is 60 provided a bridge or trestle for bracing and stiffening the wing frame. Above the middle wing supporting tube 77, which is removably secured to the body by means of flanges 78, there is provided a two-part yoke 65 tube 79, which is connected with its outer

ends to the cross-tube 77 as at 80, then ascends toward the center where the two sections are joined by flanges 81. Vertical brace tubes 82 are interposed at suitable intervals between the members 79 and 77. The 70 beam 79 is further braced against a forward wing supporting member 83 and against a rearward wing member 84 by ties or stays 85. The wings, thus, together with the wing trestle, form a rigid trellis structure. Every pulley is preferably provided with flanges or side wheels to prevent the cable from slipping off.

What I claim is:

1. In a flying machine, in combination, 80 the machine body, a car pendulously suspended therefrom restricted to swaying only laterally of the longitudinal axis of the machine, and a transmission cable, elastically secured with both ends to said car and intermediately supported at points located outside of the axis of oscillation of the car and at some distance therefrom.

2. In a flying machine in combination with the body, a cross-pendulating car, a 90 cable, the ends thereof resiliently secured to said car and otherwise operatively guided by pulleys located laterally of the axis of oscillation of the car, and a rotatable member in connection with said car and supporting said cable intermediately of said 95 guide pulleys.

3. In a flying machine in combination with the body, a cross-pendulating car, a cable operatively guided over pulleys located outside of the axis of oscillation of said car and at some distance therefrom and its ends resiliently secured to the car, a rotary member around which said cable is wound intermediately of said guide pulleys, 100 and manually operated means in connection with said rotary member for operating the latter.

4. In a flying machine, in combination with the body, a cross-pendulating car; a 110 cable operatively guided over pulleys located outside of the axis of oscillation of said car and at some distance therefrom and its ends resiliently secured to the car, a rotary member adapted to operate said 115 cable, hand-operated means in operative connection with said rotary member, and means for rigidly connecting said hand-operating means to said car.

5. In a flying machine, in combination 120 with the body, a car, hangers for cross-pendulously suspending said car from said body, braces rigidly attached with their lower ends to said hangers, and thrust bearings for journaling the upper ends of said braces in the axis of oscillation of the said car hangers.

6. In a flying machine, in combination with a cross-pendulous lever, a cable elastically secured at both ends to the lower end. 130

- of this lever and operatively guided over points located without the axis of oscillation of said lever and at some distance thereof, said cable coöperating with a rotatable member located in the axis of oscillation of said lever, stabilizing planes hinged to the machine wings, and means for transmitting the movement of said rotatable member to said stabilizing planes.
- 5 7. In a flying machine, in combination with the winged body, a cross-pendulating lever, a cable, elastically secured with both ends to the lower end of said lever, and operatively guided over pulleys located outside of the axis of oscillation of said lever and at some distance therefrom, a drum rotatable about the axis of oscillation of said lever and said cable being operatively passed around said drum, two further cables 15 coöperating with said drum, a stabilizing plane hinged to each wing, a cable pulley for each of such stabilizing planes situated on the hinge axle of the respective planes, the ends of the two additional cables, being 20 respectively attached in pairs to one of said cable pulleys.
8. In a flying machine, a cross-pendulating lever, a rotary member located in the axis of oscillation of this lever, a rotary member located without the axis of oscillation of this lever, a two-part cable transmission, one section thereof intermediately secured to the first rotary member and with its ends to the lower end of said lever, 30 and the other section intermediately secured to the second rotary member and with its ends also to the lower end of said lever, stabilizing planes hinged to the wings, and means for transmitting the movement of 35 the first rotary member to the said stabilizing planes.
9. In a flying machine, a cross-pendulating car, a cross-pendulating lever, both having the same oscillation axis, a rotary member in this axis of oscillation and a rotary member outside thereof on said car, a two-part cable transmission, one part thereof coöperating with the first rotary member and secured with its ends to the lower end of 40 said lever, and the other part guided over points situated in or near the axis of oscillation, coöperating with the second rotary member and secured with its ends to the lower end of said lever, stabilizing planes hinged to the wings, means for transmitting 45 movement from the first rotary member to said stabilizing planes, hand operated means for actuating the second rotary member and means operated automatically by the relative angular displacement of wings and car 50 for actuating said second rotary member.
10. In a flying machine, a cross-pendulating car, a cross-pendulating lever, both having the same axis of oscillation, a rotary member in this axis of oscillation and a rotary member outside thereof on said car, a two-part cable transmission, one part thereof coöperating with the first rotary member and secured with its ends to the lower end of 55 said lever, and the other part guided over pulleys situated in or near the axis of oscillation, coöperating with the second rotary member and secured with its ends to the lower end of said lever, stabilizing planes hinged to the wings, means for transmitting 60 the movement of the first rotary member to said stabilizing planes, a cable coöperating with a third rotary member and resiliently secured with its two ends to the car and guided over points located outside of the 65 axis of oscillation and distanced therefrom, and manually operated means in coöperation with the third rotary member and rigidly connectable to said car.
11. In a flying machine, a cross-pendulating car, a cross-pendulating lever, a cable elastically secured with its ends to the said car and guided over points located without the axis of oscillation of the car and at some distance therefrom, stabilizing planes hinged 70 to the wings, means for adjusting the said planes by the oscillations of said lever, and means for rigidly connecting said pendulous lever and said pendulous car in any relative angular position.
- 80 In testimony that I claim the foregoing as my invention, I have signed my name in presence of two subscribing witnesses.
